[57] CLAIM

The ornamental design for a guitar body, as shown and described.

DESCRIPTION

FIG. 1 is a left side elevational view of a guitar body showing my new design;

FIG. 2 is a front elevational view;

FIG. 3 is a bottom plan view; and

FIG. 4 is a view like FIG. 2 of a modified form of a guitar body showing my new design wherein a pair of sound holes replaces the single circular sound hole. The rear of the guitar body is flat.

Fig. 1.

Fig. 2.

Fig. 3.

Fig. 4.
